UNITED STATES PATENT OFFICE.

LUCIUS ANTON SMITH, OF TOPEKA, KANSAS.

HERNIAL TRUSS.

SPECIFICATION forming part of Letters Patent No. 690,624, dated January 7, 1902.

Application filed June 27, 1901. Serial No. 66,284. (No model.)

To all whom it may concern.

Be it known that I, LUCIUS ANTON SMITH, a citizen of the United States, residing at Topeka, in the county of Shawnee and State of 5 Kansas, have invented new and useful Improvements in Trusses, of which the following is a specification.

My invention relates to improvements in trusses; and it consists, mainly, in a novel pad 10 especially adapted to corpulent patients, novel means for applying and adjusting the pad to a patient with ease and accuracy, and novel means for attaching the pad to a wire belt or support.

15 Corpulent patients or those having overhanging abdomens have suffered greatly while wearing trusses, because when they stoop their large flabby abdomens lap over the upper edges of the pads and by reason of 20 friction and perspiration become sore and painful. In fact, in many cases patients have suffered so acutely from the cause mentioned as to be compelled to stop wearing trusses.

One of the objects of my invention is to provide 25 a truss-pad which is provided with a forwardly-projecting portion at its upper large end, said portion having a rounded side to be presented to the abdomen of a patient, and being in consequence adapted to prevent the 30 abdomen fromlapping over its edge and becoming chafed or sore.

Another object is to provide means for fastening a truss pad or pads on the body of the patient, such means being susceptible of easy 35 application and yet calculated to securely hold the pad or pads in proper position, and being, moreover, adapted to hold the pad upward against the hernia with the tension desired.

40 Another object is to provide means through the medium of which truss-pads may be expeditiously and securely connected to the fastening means in the position desired.

Other advantageous features of the invention 45 will be fully understood from the following description and claims when taken in conjunction with the accompanying drawings, in which—

Figure 1 is a perspective view of a single 50 truss embodying my invention. Fig. 2 is a detail elevation illustrating the application of

the cushion to the wire of the fastening appliances. Fig. 3 is a detail section taken on the broken line 3 3 of Fig. 2. Fig. 4 is a view illustrating the outer surface of the pad and 55 its oblique position when in use. Fig. 5 is a vertical section of the pad. Fig. 6 is a detail elevation of a modification. Fig. 7 is a view of a double truss constructed in accordance with my invention. 60

Similar letters of reference designate corresponding parts in all of the several views of the drawings.

My improved truss-pad A may be made of wood, metal, rubber, or any other material suitable to the purpose and may be either solid or hollow, as desired. It is peculiar in that it is provided at its upper large end with a forwardly-projecting overhanging portion a, the inner side of which is rounded in conformity to the remainder of that side of the pad which is presented to the body of a patient, as shown. It is also peculiar in that it is provided below the projecting portion a and in a plane considerably within the edge 75 of said portion with a preferably circular recess b. By virtue of the pad being provided with the forwardly-projecting overhanging portion rounded, as described, it will be observed that when the pad is fastened on the 80 body of a corpulent or moderately-stout patient it will support the folds of the abdomen and effectually prevent the same from lapsing over its edge, and in consequence will conduce to the comfort of the wearer of the 85 truss and enable him to stoop and move the body in various directions without liability of chafing and consequent soreness. It is obvious that while this pad is especially adapted for use upon corpulent patients it is equally 90 valuable to all persons afflicted with hernia. It is also obvious that if an ordinary pad be provided with raised side walls or flanges in place of the construction I have herein shown considerable relief will be afforded to suffering patients. 95

The pad shown is designed to cover the inguinal canal of the body, which is oblique, and consequently it is essential that the pad rest in an oblique position in conformity to 100 said canal and cover at least the internal ring thereof. It is to adapt the pad to this pur-

pose that it is cut away or hollowed obliquely at about a forty-five-degree angle with its longitudinal plane, as shown.

B is a clamping plate or keeper, of sheet metal or other suitable material, which rests in the recess b of the pad immediately below the projection a and has its side wall c let into said recess in the pad, as shown. The side wall or flange of this plate is cut away on one side about the distance illustrated, as indicated by c², to provide play-room for a holding-wire, presently described. Said plate is provided with a stud e and is connected to the pad through the medium of screws f, disposed at opposite sides of the stud, as shown. The plate B is designed to receive the loop g of the wire C, and the screws f have for their purpose to clamp the said loop against the surface b of the pad, and thereby effect a strong and durable connection of the pad to the wire and one which is not liable to become loose and permit the position of the pad to be casually changed. The wire when bent to a loop form, as represented, gives a strength and rigidity to the fastening which is not possible to be obtained by a single unbent strand.

As before stated, the pad is designed to cover the inguinal canal of the body, and when it is remembered that such canal, while lying in the same approximate direction in all persons, varies somewhat in its direction of descent the advantage of the fastening described, which permits of the pad being tilted a sufficient extent in either direction to get a proper fit, will be readily appreciated.

When desired for the sake of cheapness, the screws f may be omitted, and in lieu thereof the stud e may be provided with a screw-shank to enter the pad and connect the plate B there-

to and also bind the loop g between the plate and the pad-surface b.

It is obvious that in place of the clamping-plate and recess staples, nails with overhanging heads, or screws may be employed for holding the loop g in position.

When desirable, the pad may be what is known in the art as a "water-pad," in which event it would be provided at its outer side with a metallic or other suitable plate shaped like the outer side of the pad shown in Fig. 4, recessed, and adapted for connection with the plate B.

The wire C is bent upward and rearward from a point adjacent to the pad A and thence downward to form an arch, and at the rear end of said arch it is looped, as indicated by h, the said loop extending upwardly from the rear end of the arch. After the loop is thus formed the wire is preferably carried rearwardly a short distance, as indicated by h², and terminates in a depending arm i, which extends such a distance below the arch as to enable its lower end to rest at a point near and back of the hip-joint of the patient, this with a view of enabling the wire to hold the pad securely in position and against casual movement. The bend h² of the wire is advan-

7c
tageous in that it allows the loop h to extend forward, with the result that when the patient stoops the loop h will remain close to the side and will not project behind the body or in any other direction. On the right of the loop h and at the lower end of the arm i are provided studs k l for the connection of the upper and lower straps, respectively, of the 75 truss, as will be presently pointed out.

D is a cushion which has for its purpose to render the wire C comfortable to the body of the patient. This cushion is preferably formed of leather and comprises a portion m, which rests at the inner side of loop h and is connected thereto through the medium of a clip n, which embraces the loop, and a stiffening-plate p, which extends upwardly from the clip and is riveted to the cushion portion 80 m, a sleeve q, which receives the main portion of the wire, and a sleeve r, which receives the rearward extension h² and depending arm 85 of the loop h. In lieu of having the arch and the depending arm i of the wire extend through the extreme ends of the sleeves q r, which construction is objectionable, because of the strain upon the stitches, I prefer to make 90 apertures s in the sleeves, through which the wire passes, as shown in Figs. 1 and 3. The 95 upwardly-projecting portion may when desired be formed by a plate h', attached to and extending upward from the arch and also attached to the depending arm i', as shown in Fig. 6. In either case it hugs the side and 100 back of the patient, affords a place above the hip for the connection of the back-strap, and contributes very materially to the proper adjustment and holding of the truss on the patient.

105 E is the lower strap of the fastening means, which has an apertured portion t at one end for connection with the stud l of the arm i and an apertured portion u at its opposite end for connection with the stud e of pad A, and F is the upper strap, which is equipped at one end with an apertured portion v for connection with the stud k on loop h and at its opposite end with a stud x for adjustable connection with the lower strap.

110 The truss shown in Fig. 1 is provided with a right-side pad and is applied in the position shown in said figure—that is to say, the pad is arranged to cover at least the internal ring 115 of the inguinal canal of the body, and the wire C extends upwardly and rearwardly from the pad, this being advantageous, since a leverage is formed so that the upper strap F can be adjusted to hold the pad upward against the hernia with the tension desired. The cushion-covered portion of the arch rests against the hip of the patient and by reason of its curvature conforms closely to the body, while the upwardly-projecting portion h rests against the hip in the rear of the crest of the ilium, 120 and the lower end of the arm i rests at the rear and close to the hip-joint. From this it follows that said upwardly-projecting portion h and arm i of the wire contribute materially 125 130 135

to the security of the fastening of the pad on the body. The upper strap F is passed around the body at the waist and connected to the stud x on the lower strap E, and, as before described, it is adapted, by reason of the leverage afforded by the upwardly and rearwardly extending wire, to be adjusted so as to hold the pad upward against the hernia and under the desired tension. The strap E is passed around the body over one hip and connected to the stud e of the pad. The closer the upper strap is buttoned to the pad the lower will the bottom strap rest around the back, and the further said upper strap is buttoned from the pad the higher will be the lower strap around the back.

When two of the springs C and two pads A are employed to form a double truss, the pads will of course be oppositely inclined and a single strap will be employed to connect the pads at the front of the patient, while two straps will be employed to connect the portions h and arms i of the two wires at the back of the patient, all as shown in Fig. 7.

I prefer to form the spring C of a single piece of wire, as shown; but I do not desire to be understood as confining myself to such construction, nor to forming the wire of one piece of any material, since, as before stated, an upwardly-extending plate or bar h', connected to the arch and also to the arm i', as shown in Fig. 6, may be employed in lieu of the loop h. I also do not desire to be understood as confining myself to the specific construction and relative arrangement of the several parts embraced in the present and preferred embodiment of my invention, as such changes or modifications may be made in practice as fairly fall within the scope of my claims.

Having described my invention, what I claim, and desire to secure by Letters Patent, is—

1. A truss-pad having a convex surface at one side, and a surface at its opposite side adapted for the connection of fastening means, and also having a forwardly-projecting upper end overhanging the latter surface.

2. A truss-pad having a convex surface at its opposite side, adapted for the connection of fastening means, and also having the forwardly-projecting, upper portion overhanging the latter surface; the upper side of said overhanging portion being convex or rounded in conformity to and forming a continuation of the convex side of the pad.

3. A truss-pad having a forwardly-projecting overhanging portion at its upper end, and also having a recess arranged immediately below said portion, and in a plane considerably within the edge thereof; in combination with a clamping-plate having its side wall arranged in the recess, a wire for pressing the pad against a hernia and provided with a loop interposed between the plate and the recess of the pad, and a screw passed through the plate and the loop of the wire and into the pad

for clamping the loop of the spring between the plate and pad.

4. In a truss, the combination of a pad having a recess in one of its sides, a clamping-plate having its side wall arranged in said recess, the belt-wire comprising the arch, the upwardly-projecting loop at the rear end thereof, the arm depending from the loop, and the loop g at the forward end of the arch; said loop being interposed between the clamping-plate and the pad, and means passed through the loop g of the belt-wire and connecting the clamping-plate and the pad. 70 75 80

5. In a truss, the combination of a pad, and a wire connected thereto and comprising the arch, the upwardly-projecting loop at the rear end thereof, and the arm depending from the loop. 85

6. In a truss, the combination of a pad having a forwardly-projecting overhanging portion at its upper end, rounded on its upper side, a wire for pressing the pad against a hernia, a clamping-plate disposed obliquely on the pad, and having its side walls arranged in the recess thereof whereby said pad is held in an inclined position, and an adjustable connection between the plate and pad for clamping the plate on a portion of the wire and holding 95 the pad thereto. 90

7. In a truss, the combination of a pad, a wire connected thereto and having the curved arch extending rearwardly from the pad, and also having the upward projection at the rear end of the arch and the arm depending from said portion, and straps for securing or fastening the pad and wire on the body of a patient. 100

8. In a truss, the combination of a pad, a wire connected thereto and having the curved arch extending rearwardly from the pad, and also having the upward projection at the rear end of the arch, and the arm depending from said upward projection, a cushion of suitable material applied to the wire, and straps for securing or fastening the pad and wire on the body of a patient. 105 110

9. In a truss, the combination of a pad, and a wire connected thereto and having the arch, the upward projection at the rear end of the arch, and the arm depending from said upward projection. 115

10. In a truss, the combination of a pad provided with a stud, a wire connected thereto and comprising the arch, the upwardly-projecting loop at the rear end thereof, and the arm depending from the loop; said wire being provided on its loop and depending arm with studs, a cushion of suitable material applied 120 to the wire, and straps for securing or fastening the pad and wire on the body of a patient. 125

11. In a truss, the combination of a pad, a wire connected to the pad and comprising the arch, the upwardly-projecting loop at the rear end thereof, and the arm depending from the loop, the cushion having the portion arranged at the inner side of the loop of the spring, and also having sleeves receiving the arch and de- 130

pending arm of said wire, a clip connected to the loop and having a resilient tongue connected to the portion of the cushion at the inner side thereof, and straps for securing or 5 fastening the pad and wire on the body of a patient.

In testimony whereof I have hereunto set

my hand in presence of two subscribing witnesses.

LUCIUS ANTON SMITH.
